UNITED STATES PATENT OFFICE.

FRED I. GETTY OF JENNINGS, LOUISIANA.

PUMP.

1,036,095.

Specification of Letters Patent. Patented Aug. 20, 1912.

Application filed September 5, 1911. Serial No. 648,589.

To all whom it may concern:

Be it known that I, FRED I. GETTY, a citizen of the United States, residing at Jennings, in the parish of Calcasieu and State of Louisiana, have invented certain new and useful Improvements in Pumps, of which the following is a specification.

This invention relates to improvements in centrifugal pumps, and more particularly to the construction disclosed in my co-pending application for patent filed Nov. 4, 1910, Ser. No. 590,698.

The object of the invention is to provide improved means for preventing the water from escaping between the periphery of the impeller and its casing and thereby exerting vertical pressure on the said impeller, the object being to increase the efficiency of the pump and relieve the bearings which support the shaft and impeller from the excessive and destructive pressure of the water referred to.

A further object of the invention is to provide improved means for supporting the pump casing in the pit, to provide for adjustment and maintenance of the parts in proper relation to insure an absolute watertight connection and to make the casing absolutely stable to withstand the strain incident to the operation of the pump.

A further object of the invention is to provide improved means for supporting the bearings in the pump casing whereby to afford convenience in assembling the parts, and to insure a stable construction.

A further object of the invention is the construction of a pit body having a base formed integral therewith and adapted to support the housing of the pump, the said pit body having provision at its upper end for supporting the shafting and impeller of the pump to the end that the proper vertical relation between said housing and said impeller will be maintained.

The invention also comprehends improvements in the details of construction and arrangement of parts which will be herein-after described and particularly pointed out in the claims.

In the accompanying drawings: Figure 1 is a vertical central section of the upper portion of the pump. Fig. 1^a is a similar view of the intermediate portion of the pump.

Fig. 1^b is a similar section of the lower portion of the pump. Figs. 1, 1^a, and 1^b, represent the entire length of the pump. Fig. 2 is an enlarged detail section of the lower portion of the pit and impeller portion of the pump. Fig. 3 is a horizontal section on the line 3--3, Fig. 2. Fig. 4 is a horizontal section on the line 4--4, Fig. 1. Fig. 5 is a detail enlarged vertical section of the pump casing, and shaft showing the first coupling above the pump. Fig. 6 is a detail enlarged view of a portion of the impeller to illustrate the shape of the inclined rib.

1 indicates a pit body secured at its lower end to a base 2. The base is provided with a concave upper surface 3, and vertical outer walls 4, the interior being concave and extending upwardly and inwardly to form a vertical annular flange 6 spaced from the outer walls 4. The flange 6, forms the wall of a centrally disposed opening 7, the lower part being threaded at 8 to receive a well tube 9.

On the top of the pit is a dome 10, to which is bolted or otherwise secured a pump head 10' which is provided with a hollow centrally disposed depending sleeve 11, to which the shaft casing is attached. The dome 10 is formed with an outlet opening 13 through which the water flows from the pit. Clamped to the depending sleeve 11, is one section 11, of a tubular casing 15. The lower end of the section 11 is threaded, and screwed thereon is a coupling 18, which also engages the threaded end of another section 19. There will be as many coupled sections as may be necessary to sink the pump to the desired depth. To the lower section 19, is connected the cap 20 of a cage 21, which forms an integral part of the casing. The cap 20 is secured to a ring 20' which is formed on its underside with a plurality of tangential grooves to receive a series of tangential blades 23, suitably spaced apart for the exit of streams of water. The bottom or base 24 of the cage tapers downwardly and at its bottom it is formed with an annular groove 25, T-shape in cross section and provided with a packing 28. The packing is held in the groove by the inwardly projecting flanges forming the T-shape groove, as clearly shown in Fig. 2 of the drawings. The base is formed

with a depending beveled flange 29, which sets loosely within the opening 7, of the base of the pit, the flange 6 thereof engaging with the packing 18 to form an effective water seal between the parts. The depending portion 29 is centrally bored to permit the water to flow from the tubing 6 into the cage 21.

The head 10 supports a pump shaft 30, and around the latter is secured a disk 31, which rests on balls 32, of a bearing formed in the pit flange 12, the latter having preferably vertically disposed flange or baffles 33. The entire weight of the impeller 15 and its shaft is supported on this bearing for which reason I have found it essential to effectively provide means for suitably bracing the shaft, and at the same time of solid angle bearings for the same in the casing, to prevent swinging or any but true rotary motion of the impeller. The construction and arrangement of this feature of my invention being described later on.

A pipe 36, communicates with a duct in the head 10, to supply the oil chamber with oil, and the bore of the head is bushed with suitable metal. The shaft 30 is made in sections and to render assembling, and repairs thereto convenient, I locate the joints 30 at particular points with reference to the sectional casing. The first section of the shaft terminates a short distance below the coupling 40, the latter coupling the end of the first section of the shaft with another section 41, the latter extending to a point some distance above the first section 19 of the casing 12, and so on throughout the length of said casing. Some distance from the 40 top of the section 19 of the casing is a upper bearing 43, driven on the section and frictionally held therein. Under the bearing 43 is a lagging 44, preferably of wood, which fits the casing section around the shaft and through which the shaft passes. At the bottom of the wood lagging is another split bearing 46, and then below the same another section of wood lagging 46, and so on down to the end of the section of 50 the casing. The opening at the bottom of the lowermost wood lagging section 46, is enlarged as at 47 and said last lagging section is supported by the plate 48 which is threaded to engage the interior threads 47, of the said casing. The bearings 43, are located at such intervals as may be found best suited to the pump structure, and it is for the purpose of properly supporting them and the wood lagging that I provide so the plate 48. The lagging sections are substantially except for the lagging may be removed from the upper portion of the uppermost section.

In each section of the casing, a series of 65 the pump shaft is mounted, and while the

shaft section is substantially the length of the casing section, the upper end of the latter in each instance is below the upper end of the former for convenience in applying tools when assembling the pump, or when removing the sections from the pit. The wood lagging and the shaft bearings are held in position by the plates 48, so that each section of the casing is a unit in itself, and will readily accommodate the shaft section and its coupling members. 75

On the lower end of the shaft is an impeller of substantially the construction shown in the previously mentioned application for patent, and comprises an upper plate 50, a lower plate 51 provided with a depending hollow annular flange 52, which registers with the opening in the depending flange 12, of the base of the casing, and between the plates 50 and 51 are arranged a series of curved tangential blades 53 to throw the water outwardly through the spaces formed between tangential vanes 23 in the cage. On the edge of the depending flange 52, are ribs 521, designed for the purpose of reducing the water in passing from the space 54, as assist in preventing a downward pressure on the impeller. A space indicated at 54, is formed between the plate 59 and the cap 20 of the casing, which is necessary for vertically adjusting the impeller.

I have found that a portion of the volume of water when forced outwardly by the blades 53, will find its way around the edges of the plate 50, and into the space 54, and because of the pressure of the water accumulating in said space a downward pressure is exerted on the impeller which tends to uplift, sweep out the bearings which support the shaft at the head of the pit. To overcome this objectionable feature, I have provided means for preventing a large portion of the water entering the space 54, and have also provided means for constantly draining such space during the operation of the pump. The space 54, formed between the walls of the lower plate 51, and the base 24, also tends to create a pressure on the impeller, and I have also provided means for overcoming this objectionable feature. 105

On the periphery of the plate 50, I arrange a series of inclined projections or ribs 56, which may be made integral with the plate, or separately therefrom and secured 120 in any suitable manner, said ribs being arranged to incline in the direction of rotation of the impeller, as shown in Fig. 2. The ribs are preferably arranged parallel to each other and may or may not be of the same depth 125 in the direction of a radius of the impeller throughout their entire length, but I prefer to make them deeper at the upper end to form converging spaces 57. As the impeller is revolved the ribs 56 tend to force the 130

water away from the entrance to the space 54, and into the volume of water being radially thrown out between the spaces of the vanes 23. But while this is effective to a degree, there will be a small amount of water pass into the space 54, and in order that it may drain into the spaces formed between the blades of the impeller, and form a part of the volume of water thrown out, 5 I provide in the plate 50, a series of openings 58, so that in case the space 54, should become filled with water, pressure will be relieved by water flowing through the openings 58, as will be readily understood. The 10 vacuum created by the revolving of the impeller tends to draw the water from the space 54, through the openings 58, so that I effectually relieve the undue pressure between the impeller and the casing and thereby prolong the life of the bearings in the 15 head of the pit.

On the periphery of the lower plate is formed a series of projections or ribs 59, which incline in the direction of the rotation of the impeller, and the reverse of the inclination of the blades or ribs 56, on the plate 50. The same action takes place in reference to these ribs as that of the ribs 56, so that the ribs 59, will effectually tend 20 to lift the water which would ordinarily pass into the space 51^a, below the impeller and force it back into the volume of water passing out through the vanes 23. As has been stated in reference to the water passing 25 into the space 54, it is impossible to prevent some of the water from passing into the space 51^a, but a large proportion of what would pass is directed through the openings between the vanes, so much that undue pressure 30 on the impeller is avoided, and the small supply entering the space will be drawn into the impeller through the space 61, formed between the depending flange 29 and the base 24.

45 In practice it may be desirable to omit the vanes 59 on the periphery of the lower flange 51, in order to create a pressure in the space 51^a with water and thereby counteract or balance the downward thrust of the impeller.

In operation, power is applied to the pulley at the upper end of the pump shaft and the impeller is rotated in the direction of the arrow shown in Fig. 2. The blades of 50 the impeller create a vacuum in the usual manner and draw the water upwardly from the well tubing 9, and throw it out in the direction of the rotation of the impeller in the course it would assume when centrifugally 55 thrown by the blades of the impeller through the openings between the vanes 23. The water is permitted to flow from the vanes 23, in tangential streams into the passage formed between the vanes and the walls 60 of the pit, which tends to elevate it in a ro-

tary and spiral manner from the bottom to the top of the pit, as clearly set forth in my prior application. As the impeller revolves, the vanes or projections 56 and 59, act on the water which tends to pass upwardly and downwardly from the impeller, and causes the same to be directed into the volume of water thrown outwardly by the blades. The water which passes the vanes 56, and finds its way into the space 54, will be drawn 70 through the openings 58, and will be forced outwardly from the impeller with the greater volume of water passing therefrom. The water which passes into the space 51^a, will be drawn into the main volume of water 75 through the slight space 61, as previously described. Hence the pressure which may remain against the walls of the impeller by the small amount of water which will pass the vanes 56 and 59, will about equalize the pressure, consequently no undue strain 80 downwardly on the impeller will occur and the bearings of the shaft in the head of the pit will not be destroyed, as would otherwise occur. When the shaft 30, is revolved the 85 balls 32 and the disk associated therewith forming part of the bearing will also revolve and agitate the oil in the chamber 12. The rotary motion imparted to the oil by the moving parts is broken by the ribs or baffles 90 33, which causes the oil to maintain its level in the oil chamber and insures the shaft being 95 thoroughly and continually lubricated by a sufficient quantity of oil in contact therewith as long as the said oil is being 100 fed to the pump.

The arrangement of the lagging in the casing and the bearings therein is of the utmost importance in a pump structure of this character, inasmuch as each section of the casing is a unit in itself, and affords great convenience in assembling the pump or when removing the various sections forming the 105 casing for repairs, etc.

When the bottom of the casing is seated on the flange 6, of the base of the pit, it forms an effective water-tight joint so that the water which will naturally flow to the bottom of the base will not leak through into the well tubing, nor will air be permitted 110 to pass through to destroy the action of the impeller when sucking the water from the well tubing. It may also be stated at this point that by the construction of the slot 25, the packing 26, is held rigidly in position 115 120 and cannot become displaced.

In assembling the pump, or when effecting repairs it frequently occurs that foreign substance or parts of the mechanism will be dropped into the pit, but by reason 125 of the form of the bottom of the pit 2 such accidents will not obstruct the operation of the parts or prevent the proper seating of the base 24, on the flange 6, owing to the space beneath the operating parts. 130

While I have described the vanes or projections 59, on the periphery of the lower plate 51, of the impeller, such construction is not absolutely essential in all pumps, as the pressure created by the water passing into the chamber 51^a is not so detrimental as that of the water passing into the space 54.

What I claim is:

1. In a pump of the class described, the combination of a pit, a casing including a series of vanes mounted in the pit, an impeller and shaft mounted in the casing, the top of the impeller being spaced from the casing, means projecting from the edge of the impeller to prevent the water passing through the pump creating pressure between the top of the impeller and the casing, and means provided for the escape of any water which may pass the first mentioned means.

2. In a pump of the character described, the combination of an impeller, and a casing surrounding the impeller and spaced from the top of the latter, the top of the impeller having openings to afford communication between the interior of the impeller and the space, the edge of the impeller adjacent the top having a series of spaced apart ribs.

3. In a pump of the character described, the combination of an impeller and a casing surrounding the impeller and spaced from the top of the latter, the top of the impeller having openings to afford communication between the interior of the impeller and the space, the edge of the impeller adjacent the top having a series of spaced apart inclined ribs.

4. In a pump of the character described, the combination of an impeller and a casing surrounding the impeller and spaced from the top of the latter, the top of the impeller having openings to afford communication between the interior of the impeller and the space, the edge of the impeller adjacent the top having a series of spaced apart ribs, the spaces between the ribs being deeper at the top than at the bottom.

5. In a pump of the character described, the combination of an impeller, a casing including spaced apart vanes surrounding the impeller, the lower edge of the impeller having outwardly projecting spaced apart ribs to prevent water passing between the bottom of the impeller and the casing.

6. In a pump of the character described, the combination of an impeller, a casing including spaced apart vanes surrounding the impeller, ribs projecting from the upper peripheral edge of the impeller to prevent water passing through the space between the peripheral edge of the impeller and the casing to the space between the top of the impeller and the casing.

7. In a pump of the class described, the combination of an impeller, a casing including spaced apart vanes surrounding the

impeller, outwardly projecting spaced apart ribs on the upper and lower peripheral edges of the impeller to prevent water passing above and below the impeller and to throw the water back into the pump.

8. In a pump of the class described, the combination of an impeller including a casing, spaced apart vanes surrounding the impeller the upper and lower edges of the impeller having outwardly projecting spaced apart ribs at the upper and lower edges to prevent water passing above and below the impeller, the top of the impeller being spaced from the casing and formed with openings which communicate with the interior of the impeller and the said space.

9. In a pump of the class described, the combination of a pit, a base secured to the pit, said base having an opening, the walls of which extend upwardly to form a flange, a tube secured in the bottom of said opening, a casing secured to the top of the pit and supported at its lower end by the vertical flange of the base, and an impeller and shaft mounted in the casing.

10. In a pump of the class described the combination of a pit, a base secured to the pit and formed with an inner vertical flange, the flange being spaced from the outer wall of the base and the bottom of the base being concave, a tube secured in the bottom of the base, a casing secured to the top of the pit, said casing having a depending central flange fitting in the base and an outwardly extended flange surrounding the depending flange, the outwardly extending flange being over and supported by the inner flange on the base of the pit, and an impeller and shaft mounted in the casing.

11. In a pump of the character described, the combination of a pit, a base secured to the pit and formed with an opening, and a vertical continuous flange, a tube secured in the opening, a casing secured to the top of the pit and formed in its bottom with a T slot, a packing seated in the slot and disposed between the bottom of the casing and the vertical continuous flange, and an impeller and shaft mounted in the casing.

12. In a pump of the character described, the combination of a pit, a casing mounted in the pit, a shaft and impeller mounted in the casing, bearings in the casing, the shaft, lagging filling the space between the bearings and space between the shaft and the casing, and detachable means for holding the lagging in the casing and against the bearings.

13. In a pump of the character described, the combination of a pit, a sectional casing mounted in the pit, an impeller and shaft mounted in the casing, each section of the casing having bearings for the shaft, lagging filling snugly between the bearings in each section and filling the space between the

the shaft and the walls of the sections, and means fitting in the end of each section for holding the lagging in position.

14. In a pump of the character described, 5 the combination of a pit, a casing mounted in the pit, said casing comprising a series of sections means for coupling the sections together, bearings in each section lagging interposed between the bearings, a threaded 10 element in each section to hold the lower lagging in position whereby to retain all the bearings and the interposed laggings in each section, an impeller and sectional shaft mounted in the casing, coupling members 15 for coupling the shaft sections together, said shaft extending through the bearings and the lagging, the coupling members of the shaft being located in the enlarged portion of the openings formed in the lower lagging 20 in the sections.

15. In a pump of the character described, the combination of a pit, a base secured thereto, a tube secured to the base, a head on the base, a shaft mounted in the head, an 25 impeller mounted on the end of the shaft, a casing secured to the head and supported on the base of the pit; said casing including a series of spaced apart vanes surrounding the impeller, there being a space formed 30 between the top of the impeller and the casing, said impeller having a series of projecting ribs on the periphery and formed with openings in its top to afford communication between the space and the interior 35 of the impeller.

16. In a pump of the character described, the combination of an impeller, and a casing surrounding the impeller and spaced from the top of the latter, spaced apart ribs projecting from the peripherical edge of the impeller adjacent the top having a series of spaced apart ribs, for the purpose set forth. 40

17. In a pump of the character described, the combination of an impeller and a casing surrounding the impeller and spaced from the top of the latter, the edge of the impeller adjacent the top, having a series of spaced apart, inclined ribs, for the purpose set forth. 45

18. In a pump of the character described, 50 the combination of an impeller and a casing therefor, the impeller having a depending flange spaced from the walls of the casing, said flange having a series of depending ribs.

19. In a pump of the class described, the combination of a casing, an impeller and shaft mounted in the casing, and means including oppositely inclined outwardly projecting ribs on the periphery of the impeller for preventing the water passing through the impeller by passing between the said impeller and the casing. 60

In testimony whereof I affix my signature in presence of two witnesses.

FRED I. GETTY.
